United States Patent Office.

PETER SCHULTS, OF ROCKWOOD, NEW YORK.

Letters Patent No. 94,038, dated August 24, 1869.

IMPROVEMENT IN CANT-HOOK.

The Schedule referred to in these Letters Patent and making part of the same.

To all whom it may concern:

Be it known that I, PETER SCHULTS, of Rockwood, in the county of Fulton, and State of New York, have invented a new and useful Improvement in Cant-Hooks; and I do hereby declare that the following is a full, clear, and exact description thereof, which will enable others skilled in the art to make and use the same, reference being had to the accompanying drawings, forming part of this specification.

The object of this invention is to furnish a cant-hook, for moving heavy bodies, as saw-logs, stones, &c., which shall be adapted to more general use than cant-hooks of ordinary construction; and

It consists in the construction and arrangement of parts, as hereinafter more fully described.

The accompanying drawings represent a longitudinal side view of the cant-hook, as when applied to use.

Similar letters of reference indicate corresponding parts.

A is the lever, which is plated at the point or short end, as seen at B.

C represents the hook proper.

The hook is connected with the lever, by means of the forked bolt D, which passes through the lever and plating B, and is fastened thereto by the nut E.

F is a branch of the hook, which extends back, forming (when power is applied) a second lever, for forcing the hook into or in contact with the object to be moved.

G is a flat spring, which is attached to the main lever A by means of the bolts H and D, as seen in the drawing.

This spring G bears against the branch-lever F, when the hook is applied to an object, as seen in the drawing, and serves to force the point of the hook into the wood, or to hold it to any uneven surface on a stone, while the power applied to the main lever forces the point into or in close contact with the object in a similar manner.

By this arrangement a hold may be obtained, by which a body of large diameter may be rolled and handled where the ordinary cant-hook would be entirely useless.

Having thus described my invention,

I claim as new, and desire to secure by Letters Patent—

The cant-hook, consisting of the stock or lever A, having the plated point B bevelled on its upper side, the hook C, attached thereto by the bolt D and screw-nut E, and provided with the arm F and upwardly-projecting point *a*, the angular spring G, secured to the stock by screw-bolts H and D; all constructed, arranged, and operated as herein shown and described, and for the purpose specified.

PETER SCHULTS.
